UNITED STATES PATENT OFFICE.

JEFFREY T. FERRES, OF LOS ANGELES, CALIFORNIA.

MACHINE FOR MAKING CORRUGATED PAPER.

1,106,502.

Specification of Letters Patent. Patented Aug. 11, 1914.

Application filed May 7, 1913. Serial No. 766,242.

To all whom it may concern:

Be it known that I, JEFFREY T. FERRES, a citizen of the United States, residing at Los Angeles, in the county of Los Angeles 5 and State of California, have invented a new and useful Machine for Making Corrugated Paper, of which the following is a specification.

This invention relates to improvements in machines for making corrugated paper. In such machines the paste applying roll has been mounted close to the corrugated roller over which the paper passes and applies the paste to the outermost projecting portions 10 of the corrugations in the paper, there being only the thickness of the paper between the paste applying roll and the corrugated roller with the result that when a torn place in the paper arrives between the paste 15 roll and corrugated roller, paste from the paste roll is applied through the opening in the paper directly to the corrugated roller, and this paste adheres to the roller and is very difficult to remove therefrom, 20 and one of the main objects of the present invention is to avoid this difficulty, and in the present embodiment I accomplish it by locating the paste roll at a point slightly farther away from the corrugated roller, 25 and I make provision in the paper guides to allow the paper to move a short distance away from the corrugated roller when the paper approaches the paste applying point, so that the paper thus comes in contact with 30 the paste roller and when a torn place in the paper arrives at the paste roll, the paste roll being at a distance from the corrugated roller, no paste is applied to the corrugated roller.

Another object is to provide cleanout points arranged adjustably on the scraper bar.

A further object is to journal the scraper bar in end frames arranged to enable it to be adjusted toward or from the paste roll and adapted to be turned over for cleaning.

Referring to the drawings: Figure 1 is a rear elevation of the machine showing parts broken away. Fig. 2 is a perspective of a 50 paper guide. Fig. 3 is a plan view of a portion of the machine at the scraper points. Fig. 4 is a vertical section through the machine on line $\alpha^4-\alpha^4$, Fig. 1. Fig. 5 is an enlarged section on the same plane as Fig. 55 4 of that portion of the machine adjacent to the corrugated rollers and paste roll.

As the present invention relates only to the aforementioned features, only a brief description is required of the other portions of the machine.

1 designates the frame in which are revolvably mounted two corrugation forming rollers 2 and 3, which are driven by gears 4 and 5.

6 is the paper which is to be corrugated in the machine and applied to a flat strip of paper 7. The paper 6 passes over an idle roller 8, and thence between the corrugation forming rollers 2 and 3, which act to corrugate the paper 6, as the paper passes 70 through the rollers 2 and 3. While the paper passes around the inner side of the roller 3 an adhesive is applied to it as will be described, and the paper 6 then passes between roller 3 and a roller 9, over which 75 the plain paper 7 passes, and the corrugated paper 6 is thereby brought into contact with the paper 7 and its projecting corrugated portions to which the adhesive has been applied are thus secured to the flat paper 7 80 so that the two sheets of paper issue from the machine secured together.

10 is an adhesive roller journaled in blocks 11 which are slidable in the frame 1, and is driven by a gear 12, see Fig. 5, the gear 85 12 meshing with a gear 13, the gears 12 and 13 being of a size which permits the roller 10 to be spaced a slight distance away from the roller 3, as clearly shown in Fig. 5. A series of curved paper guides 14 are arranged between roller 3 and adhesive roll 10, the latter roll having a series of grooves 15 which receive the respective guides 14. Each of the guides 14 has an inner curved edge 16, which is concentric with the roller 3 95 and has a cut out portion 17 located at a point to allow the corrugated paper 6 to spring away from the roller 3 and come in contact with the adhesive roll 10, so that adhesive is applied to the paper when the latter passes into and through the cut out portions 17. Each paper guide 14 is pivotally supported by an arm 18, which extends through a shaft 19 and is adjustably retained in position therein by a set screw 20. 100 The concentric edges 16 hold the paper against the corrugated roller 3, and the cutaway portions 17 of the paper guides permit the paper to spring away from the corrugated roller at that point, as clearly shown 110 in Fig. 5, and thus move into contact with the adhesive roller 10 and receive the appli-

cation of adhesive, after which the paper is again caused to travel close against the corrugated roller and be secured against the flat strip of paper 7. By this construction 5 the adhesive roller is kept at a distance from the corrugated roller, and thus it is impossible for any adhesive to get on to the corrugated roller. The adhesive roller 10 receives its supply from a trough 21, and in 10 order to keep the grooves 15 cleared out I provide a series of cleanout fingers 22. These are secured by a set screw 23 to a scraper 24, the latter acting to clean superfluous adhesive from the outer surface of the 15 adhesive roller 10. The scraper 24 is carried on brackets 25, which are supported by a rod 26, the rod 26 being supported by end frames 27, each end frame 27 being adjustably secured to a stud 28 by nuts 29, the 20 lower end of each stud 28 being pivoted at 30 to a lug 31 on the main frame 1. This construction is such that by regulating the nuts 29, frames 27 may be swung up or down to rock the shaft 26, and thereby swing the 25 cleanout fingers 22 and scraper 24 away from or toward the adhesive roll 10. By removing the upper nuts 29 the arms 27 may be swung upwardly to turn the shaft 26, and swing the scraper 24 and cleanout fingers 22 substantially half way around into 30 such a position that they are easily accessible for cleaning.

What I claim is:

1. In a machine for making corrugated 35 paper, paper conducting means, adhesive applying means adjacent thereto and out of contact with said conducting means, means for holding the paper in contact with the conducting means at separated areas, where- 40 by the spring of the paper between said areas causes the paper to contact with the adhesive applying means.

2. In a machine for making corrugated 45 paper, a roller over which the paper is passed, an adhesive roll located out of contact with said roller, and guide means for causing said paper to first contact with said

roller and then permit it to spring away therefrom and then cause it to contact with said roller.

50

3. In a machine for making corrugated paper, a forming roller over which the paper passes, an adhesive roll located adjacent to and out of contact with the forming roller, said adhesive roller having grooves, 55 a series of paper guides received by said grooves and guiding the paper on said forming roller, said paper guides having cutaway portions to permit the paper to move away from the forming roller into contact with 60 the adhesive roller.

4. In a machine for making corrugated paper, a forming roller over which the paper passes, an adhesive roll located adjacent to and out of contact with the forming roller, 65 said adhesive roll having grooves, a series of paper guides received by said grooves and guiding the paper on said forming roller, said paper guides having cutaway portions to permit the paper to spring away from 70 the forming roller into contact with the adhesive roll, and means projecting into said grooves for cleaning the same from adhesive.

5. In a machine for making corrugated paper, a pair of corrugated rollers between 75 which the paper is passed, an adhesive roll located opposite one of said corrugated rollers and out of contact with it, concave guides with recesses for holding the corrugated paper in close contact at separated 80 points with the latter corrugated roller, said recesses guiding the paper in contact with two portions of the corrugated roller, and permitting the paper to spring away from 85 the corrugated roller at that portion of the roller between said first mentioned portions.

In testimony whereof, I have hereunto set my hand at Los Angeles, California, this 1st day of May 1913.

JEFFREY T. FERRES.

In presence of—

GEORGE T. HACKLEY,
MARTHA M. LANGE.
